JOHN M. FITZ GERALD, OF CHICAGO, ILLINOIS, ASSIGNOR TO AUTOMATIC FLAGMAN COMPANY, OF LOS ANGELES, CALIFORNIA, A CORPORATION OF CALIFORNIA.

SIGNAL DEVICE.

1,255,831.

Specification of Letters Patent.

Patented Feb. 5, 1918.

Application filed April 3, 1914. Serial No. 829,406.

To all whom it may concern:

Be it known that I, JOHN M. FITZ GERALD, a citizen of the United States, residing at Chicago, in the county of Cook and State of Illinois, have invented certain new and useful Improvements in Signal Devices, of which the following is a specification.

This invention relates to improvements in signal devices and has particular relation to signal targets or light attention attracting means for use in connection with a signal operating mechanism of any kind. The device is especially adapted for use with signals where it is desired to move, wave or oscillate a warning or other signal means for attracting the attention of the public and warning them against danger, as at railway or street crossings or other places where the public is likely to be exposed to danger from moving vehicles, cars, trains or the like.

It is an object of the invention to provide a target formed arch shaped in cross section whereby it may be made of great strength without being unnecessarily heavy and whereby internal illumination may be provided which is capable of illuminating the usual signal lenses as well as warning signs. It is a still further object of the invention to provide a hollow signal member or target with a central bulged portion, the walls of the disk being formed of interchangeable pieces and affording space between them for the reception lamps for illuminating the device at night.

It is a still further object of the invention to provide a hollow target having central light openings and having warning signs upon the walls thereof which are outlined by transparent lights or jewels, the inner surface of the target acting as reflectors for intensifying and concentrating the light through the said light openings and jewels.

With these and other objects in view the invention comprises certain novel constructions, combinations and arrangements of parts, as will be hereinafter fully described and claimed:

In the accompanying drawing forming a part of this specification:

Figure 1 is a side elevation of a signal target constructed in accordance with the present invention.

Fig. 2 is a transverse vertical central sectional view taken through said target.

Fig. 3 is a detail sectional view through one of the jewels employed in the warning sign, the same being shown upon an enlarged scale.

The target of the present invention is adapted for use upon various kinds of signals and while it may be employed upon stationary devices, it is especially well adapted for use where the target is intended to be movable and may be carried by a rocking or oscillating arm or device. The target is constructed with a view to being capable of withstanding strains put upon the same by the wind, and also with a view to being seen in all directions. The details and features of the invention will now be more specifically described, reference being had to the drawing in which 1 indicates a target wall, 2 a signal or light distributing lens and 3, an illuminating means usually consisting of one or more lamps.

In order that the signal member or target may be made of light material and yet of great strength, the walls 1 thereof are made conical shape and preferably circular in peripheral contour so that when the edges of two opposing conical walls are brought together as shown in Fig. 2, an edge rim 4 may be used to hold them together. The said rim is preferably formed in two sections and made V-shape in cross section as shown in Fig. 2. The rim sections are secured by riveting or otherwise, to an attaching member 5 by which the device may be secured to the arm 6 of a signal mechanism, the said signal mechanism not being shown. The adjacent ends of the rim 4 are separated and the edges of the target walls 1 are cut away at 7 within the said attaching member 5 to afford an opening through which insulated wires or conductors 8 may pass to the center of the said target. The conductors 8 are used to supply an electric current for one or more lamps at the center as indicated at 3.

The attaching member 5 may be lined at 9 with a fiber bushing or other insulating material as desired. The upper end of the said attaching member 5 is also usually provided with internal screw threads 10 whereby it may be screwed upon the correspondingly threaded end of the supporting arm 6. The rim sections 4 are preferably drawn together at the bottom of the target walls 1 by means of brackets 11 secured thereto and

a connecting screw bolt 12 which joins the said brackets. A space 13 is usually left between the meeting ends of the rim sections between said brackets and a registering cut 5 a-way portion 14 is arranged opposite said space in the edges of the target walls 1 so that a small ventilating opening is thus provided for the device. The lamps 3, usually two in number may be of any ordinary type 10 and are generally supported upon a transverse bar or plate 15 secured within the target.

At the center of the target walls 1 openings 16 are provided which are adapted to 15 be closed by the lenses 2. The openings 16 are usually surrounded by out-turned cylindrical flanges formed upon the target walls 1 and securing flanges are also provided at the outer edges thereof as at 17. The lenses 20 are held in position upon said flanges by flanged straps 18. The said flanged straps form channel straps which may be drawn about the edges of the flanges 17 and the lenses by means of screw bolts 19 which connect brackets 20 fastened to the ends of said straps. The said straps 18 also preferably receive the peripheral securing flanges 21 of shield hoods 22 which are applied over the lenses. Such shielding hoods are usually 30 necessary when the target is employed at a railway crossing so as to prevent the moving signal light from being seen by a car or train approaching from either direction upon the railroad. 35 The target is also provided upon its outer surface with warning signs usually in form of words indicating that there is danger and that parties attempting to pass should stop. These words are generally painted in 40 colors contrasting with the color of the target so that they may be readily seen in the day time. Thus, the said words may be painted in white upon red target walls. It is needful however that one or more of the 45 warning words be brought to view at night and for this purpose the target walls which in the present invention are provided with a series of openings 23 arranged so as to follow the letters of the warning word or 50 words and thus outline the same when light passes through them. The openings 23 are preferably covered by transparent pieces or jewels 24. The jewels are generally formed of glass of any desired color and are secured 55 in the openings 23 by rims 25 made approximately S-shape at cross section so as to snugly fit upon the edges of the openings 23 and also upon the edges of the jewels 24, as will be clearly understood by reference 60 to Fig. 3 of the drawing. It will be apparent that one or more of the words may thus be illuminated as found desirable, all within the spirit of the invention.

The structure above set forth is possessed 65 of a number of advantages, especially when

used for an oscillating signal or warning target and when carried by a swinging or vibrating arm. By the conical shape of the target walls, a large central opening is provided within the device and an arch shaped 70 mechanism is afforded which is possessed of the required strength without being made of heavy material. The walls of the said target may be made interchangeable and thus kept in stock so that one or both of them 75 may be readily replaced at any time. By painting the inner surface of the said walls with white paint or surfacing it with other bright material, the said inner concave surfaces of said walls become reflectors and 80 greatly intensify the illumination of the warning lenses and the word outlining jewels. For this reason lamps of lower candle power may be employed than would otherwise be required. By the construction of 85 the device also the lamps required for the lenses may be made to do the double duty of causing the warning words to be apparent from the exterior of the device.

The bulged formation of the said target 90 also makes it possible to see the device in all directions since it is of considerable width and will be readily apparent though it is viewed from the edge. The shielding hoods 22 prevent the moving lights which would 95 otherwise show up and down the railroad track, from being seen by the operators of cars or trains and thus being mistaken by them for signals intended to control the movement of their cars or trains. The 100 mounting of the target walls and also of the lenses is of such a character that any portion of the device may easily be reached for removal and replacement. The lamps which are usually of the ordinary electric 105 type may also be readily reached for renewal if they become burnt out. It will be apparent that the minor details of the device may be altered and mechanical equivalents thereof employed without departing 110 from the spirit of the invention.

What is claimed is:—

1. A signal target having opposing conical reflector walls applied upon each other and provided with light openings in their 115 apexes and means fitting upon the peripheries of said conical walls for separably holding them together.

2. A signal target comprising opaque wall members, spread apart at the center and 120 coming together at the edges, means for crowding and holding the said edges upon each other, the central portion of said wall members being provided with openings through which light may be distributed, 125 lenses in said openings and lamps mounted interiorly of the target for illuminating the said lenses.

3. A signal member having opposing conical walls applied together at their edges and 130

forming an interior space and having apex openings and means for illuminating the said openings.

4. A target for signals comprising a hollow member having opposing conical walls and having central signal light openings in their apexes opposite to each other and auxiliary word or sign spelling openings, the said conical walls reflecting light through said openings, and the apex openings and giving warning signals and words clearly apparent at night.

5. A signal target device comprising target walls having inner opposing concave reflector surfaces and having apex openings and auxiliary openings to one side of said apex openings and arranged to outline letters forming signal words, transparent jewels mounted in said openings and lamps mounted between the target wall reflectors for illuminating the said jewels and making the words clear at night.

6. A signal target device comprising conical target walls applied together to form an interior light chamber, said walls having lens openings at their apexes, lens holding flanges surrounding said openings, lenses

adapted to fit thereon and securing straps for binding said lenses to said flanges.

7. A signal target comprising opposing signal walls spread apart centrally and having openings formed therein, lenses mounted in said openings, lens shielding hoods mounted over said lenses, channel straps arranged to hold the said hoods and the said lenses upon the openings in the walls of the target and lamps mounted within said walls for throwing rays of light through the said lenses at night.

8. A signal target comprising opposing conical walls having light distributing faces therein, edge members having inner grooves adapted to fit on the edges of said conical walls, means for drawing said edge members toward each other for binding the conical members together, and interior illuminating means supported in the target.

In testimony whereof, I have hereunto set my hand, in presence of two witnesses.

JOHN M. FITZ GERALD.
